Filed Aug. 1, 1966, Ser. No. 3,292

Term of patent 14 years

(Cl. D22—7)

FIG. 1

FIG. 2

FIG. 4

FIG. 3

FIG. 5

FIG. 1 is a side elevational view of a gun having a telescopic sight mount, showing my new design;

FIG. 2 is a side elevational view of the rear and front sight mounts which are shown positioned on the gun in FIG. 1;

FIG. 3 is a top plan view of the two sight mounts of FIG. 2;

FIG. 4 is a front elevational view taken from the right of FIG. 2; and

FIG. 5 is a rear elevational view taken from the left of FIG. 2.

The essential features of the design reside in the telescopic gun sight mounts shown in full lines.

I claim:

The ornamental design for a gun having a telescopic sight mount, as shown and described.
